US00D738525S

(12) **United States Design Patent**
Muraoka et al.

(10) **Patent No.:** US D738,525 S
(45) **Date of Patent:** ** Sep. 8, 2015

(54) **PRE-PROCESSING MACHINE FOR SAMPLING**

(71) Applicant: **SHIMADZU CORPORATION**, Kyoto (JP)

(72) Inventors: **Hiroshi Muraoka**, Kyoto (JP); **Shin Nakamura**, Shiga (JP); **Nobuhiro Hanafusa**, Kyoto (JP)

(73) Assignee: **SHIMADZU CORPORATION**, Kyoto (JP)

(**) Term: **14 Years**

(21) Appl. No.: **29/512,984**

(22) Filed: **Dec. 24, 2014**

(30) **Foreign Application Priority Data**

Sep. 3, 2014 (JP) 2014-019351

(51) **LOC (10) Cl.** 24-01

(57) **CLAIM**

The ornamental design for a pre-processing machine for sampling, as shown and described.

DESCRIPTION

FIG. 1 is a perspective view of a pre-processing machine for sampling showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, shown in use state;

FIG. 10 is another perspective view thereof, shown in use state;

FIG. 11 is a front view thereof, shown in use state;

FIG. 12 is a rear view thereof, shown in use state;

FIG. 13 is a left side view thereof, shown in use state;

FIG. 14 is a right side view thereof, shown in use state;

FIG. 15 is a top view thereof, shown in use state; and,

FIG. 16 is a bottom view thereof, shown in use state.

The broken lines in the drawing show unclaimed environment only and form no part of the claimed design.
